(57) **CLAIM**

The ornamental design for an aromatic nebulizing diffuser with auto-light regulator, time-regulator and music player, as shown and described.

DESCRIPTION

FIG. 1 is a perspective view of the aromatic nebulizing diffuser with auto-light regulator, time-regulator and music player embodying the design;

FIG. 2 is a front view of the aromatic nebulizing diffuser with auto-light regulator, time-regulator and music player embodying the design shown in FIG. 1;

FIG. 3 is a rear view of the aromatic nebulizing diffuser with auto-light regulator, time-regulator and music player embodying the design shown in FIG. 1;

FIG. 4 is a left side view of the aromatic nebulizing diffuser with auto-light regulator, time-regulator and music player embodying the design shown in FIG. 1;

FIG. 5 is a right side view of the aromatic nebulizing diffuser with auto-light regulator, time-regulator and music player embodying the design shown in FIG. 1;

FIG. 6 is a top plan of the aromatic nebulizing diffuser with auto-light regulator, time-regulator and music player embodying the design shown in FIG. 1; and,

FIG. 7 is a bottom view of the aromatic nebulizing diffuser with auto-light regulator, time-regulator and music player embodying the design.

The broken lines are included for the purpose of illustrating portions of the aromatic nebulizing diffuser with auto-light regulator, time-regulator and music player that form no part of the claimed design.
